APPARATUS FOR AND METHOD OF DOUBLE
WEB COATING

Carle J. Merrill, Portland, Maine

Application April 12, 1937, Serial No. 136,356

10 Claims. (Cl. 91—18)

This invention relates to the art of coating paper and more particularly to the coating of both sides of a traveling web or sheet and the distribution of a uniform coating over the sheet by means of air-jets or air-doctors. I am aware that an air-doctor or air-jet has been employed to distribute and smooth coating materials on one side of a traveling web or sheet. My invention has to do with the use of air-jets in somewhat different form and arrangement for distributing coating on both sides of a traveling web, simultaneously.

Reference is made to the following figures:

Fig. 1 shows one conventional method for applying coating materials by means of two superimposed rolls after which the web passes between the double air-jet arrangement above mentioned.

Fig. 2 shows a somewhat different means for applying coating to both sides of the web and an air-jet arrangement similar to Fig. 1.

Fig. 3 shows a third arrangement of coating applying means and the use of air-jets similar in design to Figs. 1 and 2.

Fig. 4 illustrates an arrangement for applying coating to traveling web, similar to that shown in Fig. 1, but a somewhat different means of air-jet application for smoothing the applied coating.

Fig. 5 illustrates an arrangement similar to those of Figs. 1 and 4, but with a different means of air-brush application.

I am committed to no particular method of applying the coating to the traveling web and the illustrations above referred to, are given simply to show conventional methods of applying coating to the web, after which it must be smoothed by some subsequent operation. Most, if not all, of the conventional means of applying coating leaves a deposit of coating on the web of uneven thickness, with ridges and ripples and thick and thin spots varying according to the condition of the coating on the application rolls.

It is the purpose of my invention to smooth out this uneven coating condition on the web, simultaneously, on both sides, by means of a jet of air properly directed against and on the web, with suitable means for disposing of the air impinged on the web by the jet and what is more important, to dispose of the coating materials removed from the web and particularly, that part of the liquid coating which may become mixed or atomized by the force of the air-jet.

The successful use of a jet of air for distributing and smoothing the coating material on a traveling web depends considerably on the maintenance of the web in a predetermined and con-

stant position relative to the jets on both sides of the web. Where only one side of the web has been coated, it is readily possible to pass the uncoated side of the web over a guide or roll, which will hold it in a predetermined position in relation to which the location of the air-brush can be definitely fixed. With a double coated web, however, or one where the coating material has been applied to both sides, it is not possible to pass this over a roll without seriously affecting or completely destroying and disrupting the surface coating already applied. One particular and important feature of my invention is the provision of means to hold the double coated web in proper position relative to both air-jets without mechanically contacting the sheet or the coating thereon.

Referring to Figs. 1, 2 and 3, the traveling sheet or web passes over guide roll 1 and between or partially around coating applicator rolls 2 and 2—a. These rolls serve to apply the coating material to both sides of the traveling web 14. After leaving rolls 2 and 2—a, the web 14 passes between collector chambers 3 and 3—a, thence between air-jets 4 and 4—a, and over an auxiliary air-nozzle 6, and a deflector plate 7.

The importance of maintaining the web 14 in central position between the air-jets 4 and 4—a has already been mentioned. This is accomplished by use of an air-jet 6 extending the entire width of the sheet or web, and immediately behind which is a deflector plate 7, which also extends the entire width of the sheet. Air, at high velocity, is forced through a narrow slot or orifice in the nozzle 6, passing under the sheet 14, and over the top surface of deflector 7. The relation of the orifice in the nozzle 6 to the deflector plate 7, results in a thin film of air being projected between the sheet 14 and the deflector 7, this sheet or film of air being uniform in thickness over the entire width of the sheet, thus holding the sheet 14 level and straight.

It will be noted, that the outer end of the deflector 7 curves away or downwardly from the sheet 14. This downward curve forms in effect, a suction area, resulting from the air passing between the sheet and the deflector, tending to hold the sheet 14 down at this point, and preventing any tendency of the sheet to move upwardly. The thin jet or stream of air passing from the nozzle 6, over the highest point of deflector 7, effectively maintains a fixed distance between the deflector 7 and the sheet 14, without permitting or allowing either any part of the deflector 7 or of the nozzle 6 to come in contact with the sheet 14, or the coating material thereon.

To further insure that the sheet be held in a central position between the air-jets 4 and 4-a, I provide deflector surfaces on each of the collecting pans 3 and 3-a, these being shown at 12 and 5 12-a. It will be noted that the ends farthest from the jets 4 and 4-a curve away from the sheet 14 in a manner similar to the deflector 1, and the purpose of this and the operation and effect on sheet 14 of these deflector portions 12 and 12-a is the same as that already described 10 of the deflector 1.

After leaving the nozzle 6 and deflector 1, sheet 15 14 is drawn along by means not shown, which means imposes a lengthwise tension on the sheet 15 or traveling web, stretching it tightly from its position over the deflector 1 to the applicator rolls 2 and 2-a. Also, the web is held between the deflectors 12 and 12-a as above mentioned. A brake, or equivalent means, on the roll from 20 which the web 14 is unwinding, enables the lengthwise sheet tension to be adjusted and maintained.

The sheet, having thus been held in a fixed 25 position, relative to the collector chamber 3 and 3-a and to the air-jets 4 and 4-a, it is thus possible to adjust the position of these respective parts so that air ejected from the slot or orifice in the nozzles 4 and 4-a, may be impinged on the sheet and utilized to smooth out the coating 30 imperfections. It will also remove any surplus coating in the form of ridges, ripples or thick portions and fill in and add coating on any thin areas.

One important and difficult problem is the 35 provision of means for caring and disposing of the surplus coating material removed from the traveling web by the air-jets 4 and 4-a. Any surplus material left on the web by the applicator rolls is blown backward over the web, by the 40 air-jets 4 and 4-a, and when too great an accumulation occurs, it is blown off the web in the form of fine drops or spray traveling with the air from the jets.

As this air is impinged on the sheet at relatively high pressure and speed, it immediately 45 expands and this together with its speed of travel, while effective in smoothing the coating material over sheet 14, must immediately be reduced in speed as soon as its work has been accomplished, in order that any entrained or atomized 50 coating material may be collected and not blown out into the room or over the adjacent machinery causing waste and other difficulties.

In order that the air after leaving the jets, 55 and doing its smoothing on its web surface may be slowed down in velocity, it is directed into collecting pans or enclosures 3. It will be noted in Figs. 1, 2 and 3 that these enclosures consist essentially of two parts. First, an entrance section 12 and 12-a, one for the upper air-jet 4 and one for the lower air jet 4-a, and an impinging and expanding area at 15 and 15-a, continuing around the entire enclosed area 3 to the inside portion of the deflector section 12.

65 These deflector portions 12 have a dual purpose. First, they cooperate with their respective air-jets to form a smoothing area on the coated material on the sheet, and second, their inwardly curved portion near the center acts to draw the air away from the sheet together with any surplus coating material, and cause it to impinge on the inner surfaces at 15 and 15-a, the coating material collecting on these areas as well as other portions of the collector pans 3 and 3-a, from 70 whence it may be drawn off in liquid form for

re-use. Normally, the surplus material in the upper collector 3, would find its way into the depressed section 16 in the deflector portion 12. In the lower collector pan 3-a, this material would normally find its way and accumulate in the bottom of this pan at 16-a. By the time the air from the jets 4 and 4-a have passed into and about the collector pans 3 and 3-a the air velocity has been sufficiently reduced so that any suspended coating material which the air may have contained has become lodged on some portion of the surface of the pans 3 and 3-a, so that the air free of coating material can pass out from the ends of these pans or be otherwise disposed of. 10

The arrangement shown in Figs. 4 and 5, are 15 primarily for the purpose of making the apparatus more compact and of reducing the distance from the applicator rolls 2 and 2-a to the air nozzle 6 and deflector plate 1, so that there will be a minimum length of traveling sheet or web 20 14, between these points effecting a more rigid support of the web between the air-jets 4 and 4-a with the same degree of web tension.

A further advantage and improvement is secured by the arrangement of Figs. 4 and 5, in 25 that the surplus coating material removed from the web 14 by the air-jets 4 and 4-a, is first impinged directly on the applicator rolls 2 and 2-a, and carried back to either the application point at the end of pipe 8 in the case of the upper 30 roll 2 or back into the pan at the bottom of roll 2-a.

In order to insure that none of the coating material removed from the web by jets 4 and 4-a escapes or is lost, the applicator rolls 2 and 2-a 35 may be surrounded by collector pans 9 and 9-a, also forming a reservoir from which the roll 2-a obtains its coating material. The air, after leaving the jets 4 and 4-a, passes between the edges 17 and 17-a of collector pans 9 and 9-a, 40 passing upwardly or downwardly around the applicator rolls until its velocity is dispersed and the entrained coating material has become lodged either on the rolls or on the inside of collector pans 9 and 9-a. The air, free from coating material 45 can then pass out thru the ends of the collector pans or be otherwise disposed of.

The arrangement of air removal and disposal in Fig. 5 is somewhat different than that shown in Fig. 4, in that two outlet passages 10 and 10-a 50 are provided with sufficiently large area adjacent to the applicator rolls to permit the air from the jets to rid itself of entrained coating material before passing out thru these openings or passages 10 and 10-a. 55

This construction leaves the applicator rolls exposed for examination. Any entrained material in the air which may tend to pass out thru the upper passage 10, will eventually, be precipitated on the sides of this passage and drained back to the web or to the applicator roll. Any coating material which may be deposited on the walls of passage 10-a can readily be collected at some low point in this passage. 60

The use of an air-jet or an air-doctor to smooth out the coating on one side of a sheet only, presents a fairly simple problem of jet and sheet location and of dispersing the air and collecting the surplus coating material. 65

However, the coating of both sides of a web or sheet simultaneously, and the smoothing of both of these coatings by air-jet methods, including the removal and collecting of the surplus coating material presents new problems. These problems 70

require the development of new methods and new apparatus, which have been herein described.

What I claim is:

1. Apparatus of the class described, comprising means for applying a coating of semi-liquid material to a traveling web, a pair of air-jets for smoothing said coating material over said web, a pair of deflector plates cooperating with said air-jets for maintaining said sheet in a predetermined position relative to said air-jets, said deflector plates forming in part an expansion chamber for air from said jets.
2. Apparatus for coating both sides of a traveling web, comprising means of applying coating material in semi-liquid form to both sides of said web, air-jets arranged to redistribute and smooth said coating materials simultaneously on both sides of said web, means for holding said traveling web in a predetermined position relative to said air-jets, said means comprising deflector plates forming a part of an expansion chamber, and air jet means for maintaining the web in a predetermined position relative to said first mentioned air jets.
3. Apparatus for applying coating materials in semi-liquid form to both sides of a traveling web, comprising means for applying the coating materials to the web in excess of actual coating requirements, means comprising two air-jets for removing the surplus material simultaneously from both sides of the traveling web, deflector plates on each side of the web cooperating with said air-jets to maintain the traveling web in a predetermined position relative to said air-jets.
4. Apparatus for coating both sides of a traveling sheet or web, comprising means for applying said coating material in semi-liquid form to both sides of said sheet or web, air-jets opposed to the travel of the web, constructed and arranged to redistribute and smooth said coating materials simultaneously on both sides of said web, by directing the air counter to web travel, means for holding said traveling web in a predetermined position relative to said air-jets both before said web reaches said jets, and also after it has passed said jets, said holding means free of mechanical contact with said web or the coating material thereon.
5. Apparatus for applying coating materials in semi-liquid form to both sides of a traveling web, comprising means for applying the coating materials to both sides of the web in excess of actual coating requirements, means comprising two air-jets for removing the surplus coating material simultaneously from both sides of the traveling web, expansion chambers on each side of the traveling web for collecting surplus coating material removed from the web by said air-jets, and deflector surfaces cooperating with said air-jets.

to maintain the traveling web in a predetermined position relative to said jets.

6. Apparatus for applying coating materials in semi-liquid form to both sides of a traveling web, comprising means for applying the coating materials to both sides of the web in excess of actual finished coating requirements, means comprising two air-jets for removing said surplus coating material said jets returning directly to said coating means a part of said surplus coating material, and expansion pans or chambers adjacent to said jets and to said coating means for collecting the remainder of the surplus coating material removed from the web.

7. The method of applying coating materials in semi-liquid form to a traveling web, which consists in applying to both sides of the web coating materials somewhat in excess of actual coating requirements, of simultaneously removing said surplus coating materials from both sides of the traveling web by streams of air, of utilizing the air from said streams to maintain the sheet or web in proper relation thereto and of applying an auxiliary air stream to the web to maintain the web in proper position relative to said streams after the web has passed the streams and the surplus material has been removed.

8. The method of applying coating materials in semi-liquid form to a traveling web, which consists in applying to both sides of the web coating materials somewhat in excess of actual coating requirements, of removing said surplus coating materials by means of streams of air positioned on both sides of the traveling web, of utilizing the air streams to maintain the traveling web in proper relation thereto and of expanding the air from said air streams to precipitate and remove coating materials from said air.

9. The method of applying coating materials in semi-liquid form to both sides of a traveling sheet or web, which consists in applying coating materials to both sides of the web, of directing streams of air against the web counter to its direction of travel, both for the purpose of smoothing said coating materials simultaneously over both sides of the web and of holding said web and the coating material thereon, free of mechanical contact with any part of the adjacent equipment.

10. The method of applying coating materials in semi-liquid form to both sides of a traveling web, which consists in applying coating materials to the web, of smoothing said coating materials over both sides of the web by directing streams of air against the web counter to its direction of travel, and without mechanical contact with said web or the coating material thereon, and of holding said web after the coating materials have been smoothed thereon, in a predetermined position relative to said aforementioned streams of air.

CARLE J. MERRILL. 60
